UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

CONTROLLER FOR ELECTRIC MOTORS.

1,352,247.

Specification of Letters Patent. Patented Sept. 7, 1920.

Application filed September 21, 1918. Serial No. 255,142.

To all whom it may concern:

Be it known that I, FRANK E. CASE, a citizen of the United States, residing at Schenectady, in the county of Schenectady, State 5 of New York, have invented certain new and useful Improvements in Controllers for Electric Motors, of which the following is a specification.

My invention relates to the control of electric motors and has for its object the provision of improved means whereby the motor may be started, stopped and generally controlled in a reliable, simple and efficient manner.

15 My invention relates more specifically to pneumatically operated controllers of the type in which a step-by-step movement is desired. In the pneumatically operated controllers difficulty has been encountered in 20 securing a positive and definite step, there being a tendency to overtravel which results in trouble at the controller contacts. In the usual type of pneumatic engine, for instance, a piston is moved forward an increment in a 25 cylinder for each step of the controller, and it is difficult to insure that the piston shall move only the predetermined distance, since owing to the inertia of the parts, there is a decided tendency to overtravel. In order to 30 overcome this difficulty and at the same time provide a pneumatic engine which is very easily controlled, I employ a multiple cylinder engine, preferably having three cylinders 120 degrees apart. The arrangement 35 is such that a complete stroke of each piston in its cylinder turns a shaft 120 degrees, which is equivalent to one step on the controller. When a stroke is completed, the pressure is left on the piston and there is 40 no tendency for the piston to either go farther or to return. It makes an absolutely definite stroke and stops. To take another step, the air must be exhausted from the cylinder, since the piston must return freely 45 and at the same time air under pressure must be admitted to the succeeding cylinder. To accomplish each step, therefore, air must be admitted to one cylinder and exhausted from the preceding cylinder.

50 In one arrangement I provide a valve, preferably an electromagnetic valve, which

is automatically operated upon each step of the controller to effect the stopping of the engine by leaving the air pressure on the cylinder which has just been operated, the 55 other cylinders, of course, being disconnected from the air pressure supply. To take another step, the operator must move his handle to operate the valve. When the engine is in a stationary position and is connected to be driven in a forward direction, 60 the operation of this valve admits air to the next succeeding cylinder through the agency of a moving distributing valve which admits air under pressure to each cylinder in 65 succession, and simultaneously with such admission exhausts the preceding cylinder which had been under pressure. When the engine is in a stationary position and connected to be driven in a reverse direction, 70 the operation of this valve admits air to the next preceding cylinder through the agency of said distributing valve and simultaneously exhausts the air from the cylinder just operated. 75

One of the important features of my improved arrangement lies in the fact that when one piston has completed a stroke to give the controller a step, one of the two remaining pistons will be in a position to 80 move the controller another step in the same direction, while the other piston is in a position to move it in the opposite direction, so that after a step is taken, by admitting air to one of the free cylinders, the controller 85 will be moved forward, while by admitting air to the other cylinder, the controller will be moved backward. This constitutes a very convenient arrangement for reversing the movement of the controller. Other objects 90 and purposes of my invention will appear in the course of the following specification in which I have shown my invention embodied in concrete form for purposes of illustration.

In the accompanying drawings, Figure 1 95 is an elevation of my pneumatic engine and controller shaft partly in section; Fig. 2 is a sectional view through the cylinders; Fig. 3 is a section on the line 3—3 of Fig. 1; and Fig. 4 is a diagrammatic view illustrating 100 the operation of the engine. Figs. 5 and 6 are views of the valve passages.

Referring to the drawings, 1 is a controller shaft driven by my pneumatic engine through crank shaft 2 and gears 3 and 4. The pneumatic engine comprises three cylinders 5, 6 and 7 mounted around the crank shaft, the center line of the cylinders being radial to the center line of the shaft, at equal distances from each other, that is, 120 degrees apart. Pistons 8, 9 and 10 fit into the cylinders 5, 6 and 7 respectively, and are arranged to drive the crank shaft with a step-by-step movement, a complete stroke of each piston corresponding to an angular movement of 120 degrees of the crank shaft. 15 Each piston is single acting, that is, it drives in one direction only and is returned freely by the operation of a succeeding piston. Instead of connecting the crank shaft with the pistons in the usual manner by a connecting rod journaled on the crank shaft, the crank is free with respect to the connecting rod, that is, the connecting rod pushes the crank shaft forward but is not attached to it. The arrangement is such that when the piston makes its complete stroke there is no possibility of its going any farther, as it is mechanically and positively stopped. In this position the movement of one of the other pistons will turn the crank shaft in one direction, while the movement of the other piston will turn the crank shaft in the other direction. The particular connection between the pistons and the crank shaft which I have illustrated comprises a triangular crank member 11 provided with rollers 12 and 13 at two of the corners, while the third corner is secured to the crank shaft 2. The pistons are provided with driving heads 14, 15 and 16, each having an elongated shank 17 pivoted to its piston at 18. These driving heads slide in guides 19 and have flat driving surfaces which engage the rollers 12 and 13.

The operation of this arrangement will be clearly understood from a consideration of Fig. 2. In this figure piston 10 has completed a stroke and the two rollers 12 and 13 both engage the flat surface of the driving head 14 at equal distances on opposite sides of the center line of the piston. The piston, therefore, has no turning moment whatever upon the crank shaft. Furthermore, any tendency of the driving head to return will not be transmitted to the crank shaft since the driving head is free of the crank. As hereinafter pointed out, there is no tendency of the driving head to return since, at the end of a stroke, pressure is left on the piston until the pressure is applied to the succeeding piston. It will be further noted from Fig. 2 that while the crank 11 is in a position of equilibrium with reference to the driving head 14, this is not true with reference to driving heads 15 and 16. The roller 12 on the crank engages the driving

head 15 to the right of the center line of thrust so that any forward movement of this head will drive the crank, and hence the crank shaft, in a counter-clockwise direction, whereas the roller 13 occupies an opposite position with reference to driving head 16, and hence a forward movement will drive the crank in the opposite direction. This same relative position of the parts is assumed at the end of each stroke so that by applying pressure to one of the two pistons which are in retracted or operative position, the crank will be turned in one direction, while by supplying pressure to the other it will be turned in the opposite direction.

In Fig. 4 I have illustrated diagrammatically the valve arrangement whereby the admission and exhaust of the air to the cylinders is controlled. These valves are normally held in an open position by springs 80 *a* and *b* respectively. Referring to this drawing it will be seen that I have provided two electromagnetic valves, which I shall designate as a whole as *A* and *B* respectively. I have shown these valves only diagrammatically in order to illustrate their function and have not attempted to show their structural arrangement. Each of these valves has two positions, one which it assumes when its winding is energized and 85 the other when it is deenergized. Valve *B* is shown for purposes of illustration and to facilitate an understanding of the arrangement as a triple valve, that is, there are three movable members 20, 21 and 22, one for each cylinder, whereas the valve *A* is shown as having only a single valve member. If the two valves *A* and *B* are both in the same position, air is admitted to a cylinder and the crank shaft will be rotated, the direction 90 depending upon the position of the valves. If they are both in the energized position, the movement will be forward, whereas if they are both in deenergized position the movement will be reversed. As shown in 95 Fig. 4, for instance, the valves are both in energized position and air is admitted to cylinder 7 so as to give a forward or clockwise rotation, but if the valves were both in deenergized position, the cylinder 6 would receive air and the direction of rotation would be reversed. If, therefore, the two valves were left in either the energized or deenergized position, the shaft would continue to rotate in either a forward or reverse 100 direction until it reached a positive stop, whereas if the valve *B* alone be moved to the opposite position without changing valve *A*, or if the two valves occupy opposite positions, the operation of the engine 105 will be stopped. The arrangement which I employ, however, is such that while valve *A* is left in one position, when a movement of the controller through more than one step 110 is desired, the valve *B* is moved to deener- 115

gized position automatically at each step and is restored by the operator, thereby giving a step-by-step movement to the crank shaft under the control of the operator.

5 The arrangement whereby the magnet winding of valve B is controlled at each step is illustrated in Fig. 4 from which it will be seen that the circuit of the winding is controlled by switch arm 23, pivoted at 10 24. This switch arm is normally held in closed position by spring 25, and is opened by the rotation of a star wheel 26, having teeth corresponding with the steps of the controller and rotating therewith. As 15 shown a projection 27 (a roller in Fig. 2) engages the teeth of the star-wheel and lifts the switch arm to open the circuit of the magnet B at contacts 28. When it is lifted, however, it is held in raised position 20 by a magnet 29, which is energized from the master controller C direct to ground. In order to take another step, therefore, the magnet 29 must be deenergized by the operator so as to permit the spring 25 to force 25 the switch member to closed position. As each step is made, therefore, the master controller being in position 2, the circuit of the winding of valve B is automatically opened by the star-wheel and is closed by the operator moving the master controller back to position 1 thereby deenergizing magnet 29 and then back to position 2 which re-energized winding B. The result is that 30 the controller takes a step at a time in accordance with the movements of the master controller by the operator from position 2 to position 1 and back.

I shall now describe in detail the arrangement of the valves and air passages where- 40 by the result above described is accom- plished. For purposes of illustration I have shown the rotating valve as being composed of an outer ring or passage 30 connected with a segmental passage 31. These two 45 passages are shown shaded and receive air from the reservoir through valve A and conduit 32. There is also an inner ring 33 and an outer segmental ring 34 connected to it, which I have shown stippled, this being 50 connected with the valve A by conduit 35. Valve A being in its energized position, therefore, as shown in the drawing, the shaded passages will receive air under pressure from the reservoir, whereas if the valve 55 A is in its upper or deenergized position, the stippled passages will receive air under pressure from the reservoir. When one passage is connected with the reservoir the other is connected with the exhaust. There 60 is also a segmental passage 36 which I have shown dotted, and which is connected to the exhaust, for purposes which will herein- after appear. It will be understood, of course, that these circular passages form 65 part of a sliding valve which revolves 120

degrees at a step, that is, 120 degrees upon each complete stroke of a piston and that the conduits connected with these passages are stationary.

Assume now the parts in the position 70 shown in the drawing, the windings of the valves A and B being energized, air under pressure will enter the conduit 32 through the valve A, thence through the outer pas- 75 sage 30 to the inner passage 31, conduit 37, 80 to the valve member 21, through the conduit 38 to the cylinder 7. Since both of the other cylinders are now connected to exhaust, (cylinder 6 through conduit 39, valve mem- 85 ber 22, conduit 40, through the passage 36 to exhaust 36', and cylinder 5, through con- 90duit 41, valve member 20, conduit 42, pas- 95sages 34 and 33 and conduit 35), the piston 10 will be forced forward rotating the crank shaft in a clockwise direction as shown in Fig. 4. The piston 8 of cylinder 5 which has just made a stroke is at the limit of its movement and is, therefore, forced back- 100 ward and the piston 9 of cylinder 6 is near its inward limit and is forced back slightly. As the piston 10 moves forward its full stroke, the shaft will be rotated in a manner heretofore described. As the shaft moves forward the magnet winding B is deener- 105 gized at the contacts 28 and the valve B moves to its opposite position, the result of which is to interrupt the passage from the conduit 37 to conduit 38 and open conduit 38' which is now in engagement with pas- 110sage 31 to conduit 38, thus maintaining air pressure in cylinder 7. The cylinder is not, however, exhausted, as air pressure remains in the cylinder. It will be understood, of course, that during this step the sliding valve will revolve 120 degrees so that the 115 end of the passage 31 passes into coöperat- 120ing engagement with the conduit 40 which, however, is now cut off from cylinder 6 by the valve member 22. If now the operator desires to move another step, he moves the 125 master controller back to position 1 to de-energize the winding 29 and then back to position 2, so that the circuit of the wind- 130ing of valve B will be again completed, thereby leaving the valves A and B once more in energized position. The passage is now open from conduit 40 to cylinder 6 so that the piston 9 moves forward and at the same time cylinder 7 is exhausted through the conduit 37 which is now in en- 135 gagement with passage 34 so that the ex- 140haust takes place through conduit 35. The result is that the controller moves forward another step. In the same way by moving the master controller to position 1 and back to position 2, the air pressure will be admitted to cylinder 5 through conduit 42, which upon the second step will be in engagement with passage 31.

Suppose now that instead of going con- 130

tinuously forward the operator wishes to reverse. Assume that the parts are in the position shown in Fig. 4, that is, a stroke has just been completed by the piston 8, but the 5 winding of the valve B has not yet been energized by moving the master controller from position 1 to position 2 and hence the valve is in its upper position. In other words, the operator has not yet moved the 10 master controller to energize the valve B to move forward but instead deenergizes the winding of valve A by master controller to off position to go backward. The valves A and B will now both be in the deenergized 15 position which is the opposite to that shown in the drawing so that the air pressure instead of being admitted to cylinder 7 will be admitted to cylinder 6 through conduit 35, passage 33, passage 34, conduit 43, valve member 22 and conduit 39. This will drive 20 the shaft in a counter clockwise direction step by step and will continue to operate automatically in that way if the operator keeps the master controller in the off position stop, the master controller is moved to position 1 and to restore the forward movement the master controller is moved to 25 position 2. In this way the controller will be moved forward one step at a time in 30 either direction at the will of the operator.

As above pointed out, the rotation of the circular passages in Fig. 4 is purely diagrammatic and illustrative, since it does not represent the actual construction of the sliding 35 valve. The mechanical construction of this valve arrangement is indicated in Figs. 1, 5 and 6 from which it will be seen that the member 44 which corresponds with the moving member in Fig. 4 is driven by a shaft 40 45 which is an extension of the crank shaft and forced toward its coöperating valve member 46 by a spring 47. These two parts of the valve, the stationary part and the moving part, having their ports and passages as indicated in Figs. 5 and 6 constitute 45 the sliding valve arrangement shown diametrically in Fig. 4. I have indicated as far as possible the ports and passages in Figs. 5 and 6 with the same numerals as 50 are used in Fig. 4. It is, therefore, unnecessary to go into further detail regarding the valve arrangement.

In Fig. 3 I have shown some of the details of the valves. Air is admitted to the air 55 chest 48 through the pipe 49, from which it is distributed by valves A and B. When the windings of the valve A are energized, air passes through the passage 50 into passage 51 and thence to the diaphragm 52 forming 60 part of the plunger 53. Secured to this plunger is a valve member 55 which corresponds with the sliding member of valve A, Fig. 4. When the windings are deenergized exhaust takes place through the exhaust 65 passage 56. In like manner the energiza-

tion of the winding of valve B moves the valve member 57 which corresponds with the three moving members 20, 21 and 22 in Fig. 4.

It will be seen that I have provided a 70 pneumatically operated controller in which a positive step by step movement is brought about under the control of the operator, the arrangement being such that there is no possibility of over travel, while at the same 75 time being very effective and simple.

While I have described my invention as embodied in concrete form and as operating in a specific manner in accordance with the provisions of the patent statutes, it should 80 be understood that I do not limit my invention thereto, since various modifications thereof will suggest themselves to those skilled in the art without departing from the spirit of my invention, the scope of 85 which is set forth in the annexed claims.

What I claim as new and desire to secure by Letters Patent of the United States, is—

1. In a circuit controller the combination with a controlling member, of means for 90 operating the same comprising a plurality of pistons, means for applying fluid pressure to said pistons successively and connections between the pistons and the controlling member whereby a complete stroke 95 of each piston advances the controlling member a step and returns another piston to operative position.

2. In a circuit controller the combination with a controlling member, of means for 100 operating the same comprising a plurality of pistons, means for applying fluid pressure to said pistons successively and connections between the pistons and the controlling member whereby a complete stroke 105 of each piston advances the controller a step and places the other piston in position to operate the controlling member when pressure is applied.

3. In a circuit controller the combination with a controlling member, of means for operating the same comprising a plurality of pistons, means for applying fluid pressure to said pistons successively and connections 115 between the pistons and the controlling member whereby a complete stroke of each piston advances the controller a step and places two other pistons in position to operate the controlling member in opposite 120 directions when pressure is applied.

4. In a circuit controller the combination with a controlling member, a crank for driving the same, three pistons acting on the said crank each of which turns the crank 125 120 degrees and means for applying fluid pressure to one of said pistons at a time.

5. In a circuit controller the combination with a controlling member, a crank for driving the same, three pistons radially disposed 130

with respect to the crank at angles of 120 degrees from each other acting on the said crank each of which turns the crank through a definite angle and means for applying fluid pressure to one of said pistons at a time.

6. In a circuit controller the combination with a controlling member, a crank for driving the same, three pistons radially disposed with respect to the crank at angles of

120 degrees from each other acting on the said crank each of which turns the crank through a definite angle and means for applying fluid pressure to one of said pistons at a time and leaving the pressure until the 15 pressure is applied to another piston.

In witness whereof, I have hereunto set my hand this 20th day of Sept., 1918.

FRANK E. CASE.
